UNITED STATES PATENT OFFICE.

GEORGE E. BURSON, OF GLENDALE, CALIFORNIA, ASSIGNOR OF TWELVE AND ONE-HALF PER CENT TO ALBERT L. BURSON, TWELVE AND ONE-HALF PER CENT TO HARVEY W. BURSON, TWELVE AND ONE-HALF PER CENT TO FRANK B. BURSON, AND TWELVE AND ONE-HALF PER CENT TO HAROLD H. BURSON, ALL OF GLENDALE, CALIFORNIA.

INTERNAL-COMBUSTION ENGINE.

Application filed November 24, 1925. Serial No. 71,107.

This invention relates to improvements in internal combustion engines.

An object of this invention is to provide a novel internal combustion engine of such construction that there are reciprocating pistons and also rotatable cylinders evenly distributing wear and facilitating the dissipation of heat.

A further object of this invention is to provide an improved internal combustion engine of the four cycle type which is of simple construction and wherein the complete engine is embodied in a single rotatable cylinder.

With the foregoing and other objects in view which will be made manifest in the following detailed description and specifically pointed out in the appended claims, reference is had to the accompanying drawings for an illustrative embodiment of the invention, wherein:

Figure 1 is a top plan view of the improved engine.

Fig. 2 is a side elevation of the engine, Fig. 3 is a horizontal section taken on the line 3—3 of Fig. 2, and

Fig. 4 is a vertical section taken on the line 4—4 of Fig. 3.

Referring to the accompanying drawings wherein similar reference characters designate similar parts throughout. The improved engine consists of a hollow housing 10 having chambers 11 formed therein for the admission of water so as to provide a water cooled jacket for the cylinder 12. The housing 10 may be supported in any suitable manner as by channel irons 13. The cylinder 12 has its ends closed by closures 14 and 15. The closure 14 is provided with a stem 16 carrying a gear 17, and as it is rigidly secured to the cylinder 12, the cylinder can be rotated by the gear. A closure 18 is threaded into the housing about the stem 16 and is hollow so that it is also water cooled. This closure provides a bearing 19 for the stem. The closure 15 has an aperture through it, and adjacent it there is a closure 20 similar in construction to the closure 18. Both the closure 20 and the closure 15 provide bearings 21 for the piston rod 22. Adjacent the

center of the cylinder 12 there is formed a partition 23 which carries a suitable bearing 24 for the piston rod 22 extending through it. Rigidly secured upon the piston rod are two pistons 25 and 26, these pistons being arranged upon the opposite sides of the partition 23.

An intake manifold 27 is arranged on the side of the housing 10 horizontally even with the center of the cylinder 12. In the housing 10 there are formed four inlet ports 28, 29, 30 and 31 which are arranged substantially in alignment along the length of the cylinder 12 and opposite its center. The two inlet ports 28 and 31 are arranged adjacent the end of the cylinder while the two inlet ports 29 and 30 are arranged adjacent its center, being positioned on opposite sides of the partition 23.

On the bottom of the housing 10 there is secured an exhaust manifold 32 which communicates with four exhaust ports 33 arranged vertically beneath the center of the cylinder and along its length. These exhaust ports are also arranged in the same transverse vertical planes with the inlet ports 28, 29, 30 and 31. In the housing 10 horizontally opposite the inlet ports there are formed apertures 34 for the reception of spark plugs 35. Four ports 36 are formed in the cylinder 12 in the same transverse vertical plane with the inlet and exhaust ports. These ports 36 are arranged approximately 90 deg. apart upon the circumference of the cylinder 12, and upon rotation of the cylinder they are adapted to uncover their respective inlet and exhaust ports and the spark plugs 35. The piston rod 22 is connected to a connecting rod 37 which in turn is connected to a crank shaft 38. One end of the crank shaft may be used to drive any apparatus desirable and may be provided with a clutch. The other end of the crank shaft is provided with a beveled gear 39 meshing with a gear 40 on a small shaft 80 which is rotatably mounted on the standard 41. This small shaft also carries a beveled gear 42 meshing with a beveled gear 43 on a shaft 44 which carries a gear 45 meshing with the gear 17. In this manner the cyl-

100

inder 12 is caused to rotate by the crank shaft which is rotated by the piston rod 22. It will be readily understood that any other mechanism can be employed for rotating the cylinder, but this mechanism is preferably operable by the piston rod so that the engine will be properly kept in time.

Any suitable timing mechanism can be employed for causing the four spark plugs 35 to fire in proper order.

The operation of the engine is as follows: Referring particularly to Fig. 3, the pistons are in the extreme right hand side position. The port 36 on the right hand side of the piston 25 is opposite the inlet port 30, and fuel is drawn into the cylinder 12 between the piston 25 and the partition 23 while the piston 25 is moved toward the left. The fuel which was previously admitted to the cylinder between the piston 25 and the closure 15 is compressed during this stroke. At the same time the piston 26 on the right hand side of the partition 23 is opposite its exhaust port 33 and the burned gases between the piston 26 and the partition 23 are being discharged through it. The port 36 on the right of the piston 26 is opposite its spark plug 35 which is firing at this instant so that there is occurring an explosion or burning of fuel between the piston 26 and the closure 14, forcing the piston rod 22 toward the left. When the piston rod reaches its extreme left position, the cylinder will have been rotated 90 deg. so that the port 36 which is shown on Fig. 3 as being opposite its spark plug is just uncovering its exhaust port 33. The exhaust port 36 which is on the extreme left hand end of the cylinder is uncovering its spark plug 35 and there is occurring an explosion between the piston 25 and the closure 15, forcing the piston rod toward the right. This movement of the piston 25 toward the right compresses the fuel between the piston 25 and the partition 23, exhausts the exhaust gases between the piston 26 and the closure 14, and causes fuel to be drawn into the cylinder from the port 29 to the space between the partition 23 and the piston 26. During the second movement from the extreme right position to the left of the cylinder, the explosion occurs between the piston 25 and the partition 23, the burned gases are exhausted from between the piston 25 and the closure 15, the fuel between the piston 26 and the partition 23 is compressed, and fuel is being drawn into the space between the piston 26 and the closure 14 through the inlet port 28. During the second movement from the extreme left hand position of the cylinder to the right fuel is drawn into the space between the closure 15 and the piston 25, the burned gases between the piston 25 and the partition 23 are being exhausted, the compressed fuel between the

piston 26 and the partition 23 is being fired and compression is taking place between the piston 26 and the closure 14.

By this construction it will be appreciated that the new internal combustion engine is of the four cycle type and that the complete device is embodied in a single rotatable cylinder. Furthermore, as the cylinder is completely surrounded by a water cooled housing, it will be effectively cooled and wear and heat will be evenly distributed.

It will be readily understood that any desirable lubricating system can be employed for lubricating the moving surfaces between the cylinder and the housing, the cylinder and the piston and the piston rod. Such lubricating system is preferably provided with a force pump for forcing the oil to the surfaces to be lubricated, which force pump is preferably driven by the crank shaft.

It will be understood that various changes may be made in the detail of construction without departing from the spirit or scope of the invention as defined by the appended claims.

I claim:

1. An internal combustion engine comprising a rotatable cylinder, a housing in which said cylinder is rotatable, means closing each end of the cylinder, means forming a partition centrally of the cylinder rotatable therewith, a piston rod extending through one end of the cylinder and through said partition, pistons on the piston rod on each side of the partition, there being ports formed in said cylinder on each side of the partition and adjacent each end, means providing an inlet port and an exhaust port adjacent each side of the partition adapted to be uncovered by the ports in the cylinder adjacent the partition, means providing an inlet and an exhaust port adjacent each end of the cylinder adapted to be uncovered by the ports in the cylinder adjacent its end, means for igniting the fuel in the cylinder upon each side of both of the pistons, and means for rotating the cylinder.

2. An internal combustion engine comprising a rotatable cylinder, a housing in which said cylinder is rotatable, means closing each end of the cylinder, means forming a partition centrally of the cylinder, a piston rod extending through one end of the cylinder and through said partition, pistons on the piston rod on each side of the partition, there being ports formed in said cylinder on each side of the partition and adjacent each end, means providing an inlet port and an exhaust port adjacent each side of the partition adapted to be uncovered by the ports in the cylinder adjacent the partition, means providing an inlet and an exhaust port adjacent each end of the cylinder adapted to be uncovered by the ports in the cylinder adjacent its end, means for igniting the fuel

in the cylinder upon each side of both of the pistons, and means for rotating the cylinder operable by the piston rod.

3. An internal combustion engine comprising a water cooled housing, a cylinder rotatable therein, means closing the ends of the cylinder rotatable therewith, means providing four inlet ports through the housing opposite the cylinder which are arranged substantially in alignment, means providing four exhaust ports through the housing opposite the cylinder which are arranged substantially in alignment, two of the inlet and exhaust ports being arranged adjacent the ends of the cylinder, the remaining inlet and exhaust ports being arranged adjacent the center of the cylinder, ports formed in the cylinder adapted to uncover said inlet and exhaust ports upon rotation of the cylinder, means providing a partition in the cylinder rotatable therewith, a piston rod extending into the cylinder and slidably extending through said partition, means providing two pistons upon said piston rod, one on each side of the partition, means for rotating said cylinder, and means for igniting fuel in the cylinder upon each side of both of the pistons.

4. An internal combustion engine comprising a water cooled housing, a cylinder rotatable within the housing, means closing the ends of said cylinder rotatable with the cylinder, means providing four inlet ports in said housing opposite the cylinder, one being arranged adjacent each end and two being arranged adjacent the center, means providing four exhaust ports in the housing opposite the cylinder, one being arranged adjacent each end and two being arranged adjacent the center, four spark plugs mounted on the housing, one adjacent each end and two adjacent the center, means providing a partition in the cylinder between the ports and spark plugs adjacent the cen-

ter of the housing, said partition being rotatable with the cylinder, a piston rod extending through one of the ends of the cylinder and through the partition, a piston mounted upon the piston rod upon each side of the partition, there being four ports in the cylinder, one adjacent each end and one adjacent each side of the partition, said ports being adapted to uncover the inlet and exhaust ports and the spark plugs upon rotation of the cylinder, and means for rotating the cylinder.

5. An internal combustion engine comprising a water cooled housing, a cylinder rotatable within the housing, means closing the ends of said cylinder rotatable with the cylinder, means providing four inlet ports in said housing opposite the cylinder, one being arranged adjacent each end and two being arranged adjacent the center, means providing four exhaust ports in the housing opposite the cylinder, one being arranged adjacent each end and two being arranged adjacent the center, four spark plugs mounted on the housing, one adjacent each end and two adjacent the center, means providing a partition in the cylinder between the ports and spark plugs adjacent the center of the housing, said partition being rotatable with the cylinder, a piston rod extending through one of the ends of the cylinder and through the partition, a piston mounted upon the piston rod upon each side of the partition, there being four ports in the cylinder, one adjacent each end and one adjacent each side of the partition, said ports being adapted to uncover the inlet and exhaust ports and the spark plugs upon rotation of the cylinder, and means for rotating the cylinder, said means being operable by the piston rod.

In testimony whereof I have signed my name to this specification.

GEO. E. BURSON.
